(Cl. D74—1)

To all whom it may concern:

Be it known that I, Wilbur K. Olson, a citizen of the United States, residing at Fort Madison, in the county of Lee and State of Iowa, have invented a new, original, and ornamental Design for a Fountain Pen Desk Stand Unit, of which the following is a specification, reference being had to the accompanying drawing, forming a part thereof.

Fig. 1 is a side elevational view of a fountain pen desk stand unit, showing my new design, the base being shown fragmentarily in both figures for convenience of illustration.

Fig. 2 is a rear elevational view of Figure 1.

The dominant feature of my design resides in the contour of the receptacle shown in full lines, the receptacle having an arcuately tapered closed end with a flared open end and a contrasting band encircling the receptacle at approximately the beginning of the flared portion.

I claim:

The ornamental design for a fountain pen desk stand unit, substantially as shown and described.
